MERCHANDISING DISPLAY STAND

Henry Cobbs, Box 1, Little River, Miami, Fla.

Filed Aug. 28, 1959, Ser. No. 57,362

Term of patent 14 years

(Cl. D80—9)

FIG. 2 is a side elevational view thereof.

FIG. 3 is a fragmentary vertical cross sectional view thereof, taken on line 3—3 of FIGURE 1.

I claim:

The ornamental design for a merchandising display stand, as shown.
